FLUID CHECKING DEVICE

Charles L. Bock, Chicago, Ill., assignor to Andrew Hoffman, Chicago, Ill.

Application October 6, 1933, Serial No. 692,393

11 Claims. (Cl. 16—55)

This invention relates to new and improved fluid checking devices, particularly characterized as double-acting and especially adapted for use in double-acting door closing and checking devices.

The invention is herein illustrated as embodied in a door check having in conjunction therewith spring means for closing the door.

It is an object of this invention to provide a double acting cylinder and piston construction which employs a shorter cylinder than heretofore has been possible with prior constructions, without sacrificing the working or checking stroke of the piston.

It is a further object of this invention to provide a double acting cylinder piston construction, the piston of which is formed in two parts mounted in overlapping relationship, and provided with racks for engagement with a pair of mutilated gears adapted to impart movement thereto.

It is a further object of this invention to provide in a double-acting piston and cylinder construction, a new and improved mechanical movement as a driving connection between an operating spindle and the two parts of said piston, whereby a new and improved double-acting checking operation results.

These and other objects not specifically enumerated will appear to one skilled in the art as the following description proceeds.

The invention may be more clearly understood by referring to the accompanying drawings in which:

Figure 1 is a cross sectional view in elevation of a concealed overhead double acting door check embodying as a part thereof, the improved piston and cylinder construction constituting this invention;

Figure 2 is a plan view of the device illustrated in Figure 1;

Figure 3 is an enlarged plan view in cross section of the piston and cylinder construction of this invention, and

Figure 4 is an elevational view in cross section taken on the line 4—4 of Figure 3 and looking in the direction of the arrows;

Figure 5 is a view similar to Figure 1, showing a concealed floor check for a double acting door embodying the improvement of the present invention;

Figure 6 is a plan view of the device shown in Figure 5;

Figure 7 is an enlarged elevational view in cross section taken on the line 7—7 of Figure 5 and looking in the direction of the arrows;

Figure 8 is a fragmentary plan view of the spring operating yoke embodied in the device of Figure 5, and

Figure 9 is an enlarged perspective view of the adjustable stop device embodied in the construction shown in Figure 5.

By referring to the drawings, particularly to Figures 1, 3 and 4, it will be noted that the improvement of this invention is illustrated as embodied in a fluid checking device or dash pot for door checks comprising a cylinder 1, having threaded openings 2 and 3 respectively, at each end thereof. These openings are closed respectively, by threaded plugs 4 and 5. The cylinder is provided with an enlargement 6 on one side thereof having a longitudinal duct or passage 7, which communicates at the intermediate portion of the cylinder with the interior spaces thereof and at its two ends by by-passes 8—9 and 10—11, respectively. These ducts provide for the regulated escapement of a suitable fluid such as glycerin, for instance, which is contained in the cylinder and the passage of which is controlled by suitable adjusting screws 12—13 and 14—15. Intermediate the cylinder is an upward standing cylindrical portion 16 which is closed by a cap 17, provided with a central bearing. On the opposite wall of the cylinder, in alignment with the bearing referred to, is a bearing 18 adapted to receive the lower end of shaft 19 which has its upper end extending through the bearing in the cap 17. Shaft 19 is provided with two driving gears 20 and 21, respectively, which have teeth thereon throughout only a portion of their circumference whereby to provide a set of mutilated gears. It will be noted that the driving teeth of said gears are arranged on opposite sides so that when one gear is in mesh with its corresponding rack, the other gear is out of mesh and vice-versa.

The piston is composed of two parts, 22 and 23, having respectively, piston heads 24 and 25. Each is provided with a rack 26 and 27 and a guide head 28—29, respectively, at its opposite end. The piston parts are so disposed within the cylinder that for the position of the driving shaft shown in Figure 3, both pistons are in outward positions towards the ends of the cylinder. As the result, movement of the shaft in either direction causes one or the other of the pistons to be picked up and drawn toward the center of the cylinder so that, upon reversing the movement, only that piston which has been thus moved to the central position is brought into operation in the checking action. After the pis-

ton has been moved to the end of the cylinder a continued movement of the shaft in the same direction subsequently picks up the other piston part and moves it toward the center of the cylinder and upon a reversal of the shaft, causes it to check toward the end of the cylinder in the same manner.

This construction effects a real and substantial improvement in various applications such as in door checks, because it avoids the travel of the inactive piston while the active piston is moved to accomplish the work of checking. It accordingly allows a much shorter cylinder length than would be necessary for an ordinary dumb bell double headed piston. Furthermore, it allows the mounting of both piston heads in alignment in the same cylinder which makes for a simplified and improved construction.

In the form of the invention shown in Figure 1, it will be noted that the piston construction is mounted in a housing 30, placed in the door frame 31 above the door and is connected for operation with the door by means of the slide guide 32, arm 33, spindle 34, and gears 35 and 36, the latter of which gears is mounted on the spindle 19 of the fluid checking device. The springs for closing the door are brought into operation by means of pins or other suitable connections 37, carried by the gear 36 which pins act on the flexible chains 38 and 39, connected to the springs 40 and 41, respectively.

The mechanism other than the fluid checking device, constitutes no part of the present invention but it is herein for convenience illustrated as being of the same form as that disclosed in Letters Patent No. 1,949,758 of Lewis C. Norton, issued March 6, 1934.

In the form of the invention illustrated in Figures 5 and 6, it will be noted the fluid checking device is mounted in a housing 40 which is located in the floor below the door and is connected directly thereto by means of an arm 41, and slide guide 42. The springs 43 and 44, respectively, are connected by means of a yoke 45, carried by the fluid checking spindle 19, and chains 46 and 47, respectively. These chains are adjustably attached to the spring sleeve 48 by means of the connections clearly shown in Figure 6. By these connections the springs may be wound up and adjusted, as for tension. In addition to the parts thus described, this checking device embodies a stop element 50, which is loosely mounted over the spindle 19, and is adjusted as to angular position by means of the arm 51 and set screws 52, which bear thereagainst and are threadedly mounted through lugs carried on the cylinder. This stop element is provided with seats 53 adapted to receive pins 54, carried by the end of the chains 46 and 47, so that each will be seated and come to rest when the spindle 19 is in the neutral position as shown in Figure 6.

It will be observed that the neutral position can be altered by adjusting the screws 52 and thereby altering the angular position of the stop element 50. When the shaft 19 swings in either direction, as when the door is open, one of the arms of the yoke 45 is caused to pick up its associated pin 54 and tension the spring connected thereto. During this movement, the other arm of the yoke moves away from the seat leaving the pin 54 resting in the seat 53. For the other direction of movement of the door, the reverse action takes place. This provides a satisfactory double acting spring tension while providing a

centering means for bringing the door to rest in exactly the central sill position.

By means of the adjustable stop element 50, the springs may be tensioned differently, according to the needs in use, while at the same time, causing the door to be exactly centered with respect to the door sill. The centering of the door in the form of device shown in Figure 2, is accomplished by means of the adjustable lugs 60, mounted on the side of the housing 30, which have their ends placed in cooperating relationship with the lugs 61 carried on the end link of the chain. It will readily appear that the chains will be picked up and seated under reverse movement of the door exactly as described in connection with the other modification.

In both cases, the guide slide for operating the door is mounted in a suitable slide in the bottom or top edge of the door, as the case may be, and the door is mounted for pivotal movement on suitable hinges 65 as shown in Figures 1 and 5, respectively. In controlling the dash pot action, two speeds are provided for by means of ducts 8 and 9 for one end of the cylinder and ducts 10 and 11, for the opposite end of the cylinder. By adjusting each of the screws independently one speed can be effected for the primary or general movement of the door, whereas a finer and more accurate adjustment can be made for controlling the door at the latch.

30

It will be appreciated from the above description that a very compact and efficient dash pot construction is hereby provided embodying a two part double acting piston in which the parts are arranged so that one acts at a time, whereby to reduce the required space in the cylinder or cylinder length for a given stroke of the piston heads in checking action.

This invention is not to be restricted to door closers as the piston and cylinder device herein described is useful and desirable for other purposes where a double checking action is desired. Furthermore, insofar as the claims herein are directed to door closers, they are not to be construed as limited to the particular type of closers here set forth as the invention has utility and advantage in many other types of double acting door checking devices.

I claim:

1. A fluid checking device of the character described, comprising a single cylinder and a two part double acting piston mounted for reciprocation in said cylinder, each part comprising a piston head and a rigidly extending gear rack, said gear racks being disposed between said piston heads and arranged in overlapping relationship, a pair of mutilated gears in said cylinder mounted for simultaneous rotation and in mesh with said racks, respectively, said mutilated gears being constructed and arranged to move only one of said racks at a time.

2. A fluid checking device of the character described, comprising a single cylinder and a two part double acting piston mounted for reciprocation in said cylinder, each part comprising a piston head and a rigidly extending gear rack, said gear racks being disposed between said piston heads and arranged in overlapping relationship, a pair of mutilated gears in said cylinder mounted for simultaneous rotation in mesh with said racks, respectively, said mutilated gears being constructed and arranged to move only one of said racks at a time, each of said racks having a head on its end opposite the piston head for guiding engagement with the interior of said cylinder.

75

3. A fluid checking device of the character described comprising a cylinder and a two part piston in said cylinder, each part comprising a piston head and a rigidly extending gear rack, said gear racks being arranged in overlapping relationship, means for driving said piston comprising a pair of mutilated gears, one each adapted for meshing engagement with said racks, respectively, the teeth of one gear extending throughout an arc of substantially 180 degrees and the teeth of the other gear being opposite to the teeth of the first gear and extending substantially throughout an arc of 180 degrees.

4. A fluid checking device of the character described comprising a cylinder and a two part piston in said cylinder, each part comprising a piston head and a rigidly extending gear rack, said gear racks being arranged in overlapping relationship, means for driving said piston comprising a pair of mutilated gears, one each adapted for meshing engagement with said racks, respectively, the teeth of one gear extending throughout an arc of substantially 180 degrees and the teeth of the other gear being opposite to the teeth of the first gear and extending substantially throughout an arc of 180 degrees, said mutilated gears being mounted on a single shaft.

5. A fluid checking device of the character described comprising a cylinder and a two part piston in said cylinder, each part comprising a piston head and a rigidly extending gear rack, said gear racks being arranged in overlapping relationship, means for driving said piston comprising a pair of mutilated gears, one each, adapted for meshing engagement with said racks, respectively, the teeth of one gear extending throughout an arc of substantially 180 degrees and the teeth of the other gear being opposite to the teeth of the first gear and extending substantially throughout an arc of 180 degrees, said mutilated gears being mounted on a single shaft, and mounted in bearings disposed centrally of said cylinder.

6. A fluid checking device comprising a single cylinder and a two part double acting piston, each piston part comprising a piston head and a rigid extension, said piston parts being mounted for reciprocation in said cylinder with their heads oppositely disposed in the end portions thereof, driving means in said cylinder having driving connection with each of said extensions and constructed and arranged so as to move only one of said piston parts at a time.

7. A fluid checking device comprising a single longitudinal cylinder, a pair of oppositely disposed reciprocating piston heads mounted in each end

of said cylinder, each of said piston heads having a rigid gear rack extending into the central portion of said cylinder between said piston heads, a shaft in said cylinder having a pair of mutilated gears thereon in mesh respectively with said gear racks and adapted to drive only one of said piston heads at a time.

8. A fluid checking device comprising a single longitudinal cylinder, a pair of oppositely disposed reciprocating piston heads mounted in each end of said cylinder, each of said piston heads having a rigid gear rack extending into the central portion of said cylinder between said piston heads, a shaft in said cylinder having a pair of mutilated gears thereon in mesh respectively with said gear racks and adapted to drive only one of said piston heads at a time, said gear racks being arranged in overlapping relationship having their adjacent faces in sliding contact.

9. A fluid checking device comprising a single longitudinal cylinder, a pair of oppositely disposed reciprocating piston heads mounted in each end of said cylinder, each of said piston heads having a rigid gear rack extending into the central portion of said cylinder between said piston heads, a shaft in said cylinder having a pair of mutilated gears thereon in mesh respectively with said gear racks and adapted to drive only one of said piston heads at a time, said gear racks being arranged in overlapping relationship having their adjacent faces in sliding contact and each having a portion at its end providing a guide member having sliding contact with the wall of said cylinder.

10. A fluid checking device comprising a single longitudinal cylinder, a pair of oppositely disposed reciprocating piston heads mounted in each end of said cylinder, each of said piston heads having a rigid extension projecting into the central portion of said cylinder between said piston heads, a shaft in said cylinder having driving means thereon in driving connection with each of said extensions respectively.

11. A fluid checking device comprising a single longitudinal cylinder, a pair of oppositely disposed reciprocating piston heads mounted in each end of said cylinder, each of said piston heads having a rigid extension projecting into the central portion of said cylinder between said piston heads, a shaft in said cylinder having driving means thereon in driving connection with each of said extensions respectively, said extensions being arranged in overlapping relationship and having their adjacent faces in sliding contact.
